UNITED STATES PATENT OFFICE.

ALBERT JAY GANZ, OF NEW YORK, N. Y., ASSIGNOR TO EINSON-FREEMAN COMPANY, OF NEW YORK, N. Y., A CORPORATION OF NEW YORK.

COMBINED SHIPPING, DISPENSING, AND DISPLAY BOX OR CARTON.

Application filed September 17, 1921. Serial No. 501,390.

To all whom it may concern:

Be it known that I, ALBERT JAY GANZ, citizen of United States of America, residing at 1505 Charlotte Street, New York 5 city, in the county of Bronx and State of New York, have invented certain new and useful Improvements in Combined Shipping, Dispensing, and Display Boxes or Cartons, of which the following is a specification, 10 reference being had therein to the accompanying drawings.

This invention relates to a combined shipping, dispensing and display box or carton and it has for its object the provision of an improved device of this nature constructed in such manner that it may be formed from a single piece of heavy paper or like material and will serve not only as a container for a plurality of packages or articles during shipment, but may be used to display said articles in the store and will permit of the ready dispensing of the article from the package without opening the carton.

25 Further objects and advantages of the invention will be set forth in the detailed description which follows.

In the accompanying drawings:

30 Fig. 1 is a perspective view of a package constructed in accordance with the invention showing the same set up to display the contents thereof;

Fig. 2 is a perspective view looking from the rear of the package;

35 Fig. 3 is a plan view showing the package in its closed condition and illustrating by dotted lines how the wings and easel may be swung out to display position;

Fig. 4 is a plan view of the blank from 40 which the entire carton is formed;

Fig. 5 is a perspective view showing the initial step in placing the articles to be displayed and vended in the carton; and

45 Fig. 6 is a perspective view showing a succeeding step in the assembly of the carton.

Like numerals designate corresponding parts throughout the several figures of the drawings.

50 Referring to the drawings and particularly to Fig. 4 it will be seen that the entire package is made from a blank consisting of a front 5 which is separated by the scored lines 6 from wings 7. When these wings are brought to the position illus-

trated in Figs. 1 and 2 they serve to aid in supporting the carton in upright position so that the packages 8 which are to be displayed and vended will be brought into view through a sight opening 9 formed in the front 5. The wings 7 not only serve the function of a support but they add to the ornamental nature of the article and may be printed, embossed or lithographed with such ornamental designs and advertising matter as may be desired, in the production of an attractive package. The front 5 is separated by a scored line 10 from a strip 11 which constitutes the top of the carton, see Fig. 1, and this strip in turn is separated by a scored line 12 from the back 13 of the carton. The front 5 is further separated by a scored line 14 from a strip 15 which constitutes the bottom of the carton and the strip 15 is in turn separated by a scored line 16 from a tab 17, the latter being provided with ears 18 which are adapted to enter the slits 19 formed in the back 13. The tab 17 carries an easel wing 20 which when brought to the position illustrated in Fig. 2 prevents the device from tipping over rearwardly. This easel wing is formed by suitably cutting the blank and normally the easel 20 lies flush with and constitutes a part of the blank, but when brought to the position illustrated in Fig. 2, an opening 21 is left through the tab 17 so that a merchant may, through this opening and through a corresponding and aligned opening 22 formed in the rear wall 13, have access to the packages 8, for a purpose presently to be described. The back 13 is separated by the scored lines 25 and 26 from the strips 27 and 28 which constitutes the sides of the completed carton and these strips are in turn separated by the scored lines 29 and 30 from wings 31 and 32. Recessed portions 33 are formed beneath the lower portions of the wings 31 and 32 and the back 13, these recessed portions constituting openings 34 at the lower sides of the completed carton through which openings the packages 8 may be ejected as presently described.

Fig. 5 illustrates the initial stage of filling 105 the carton. The packages to be dispensed and displayed, which may be, for example, packages of safety razor blades, blocks of chocolate, or anything else, are placed on the back 13 between the scored lines 25 and 110

26 and then the wings 31 and 32 are folded over upon the packages. When the front 5 is folded over upon the wings 31 and 32 the strip 15 is folded over to constitute the 10 bottom of the package and the wings 18 are inserted in the slit 19, as illustrated in Fig. 2. During shipment the wings 7 may be folded over upon the front 5, as illustrated in Fig. 6.

10 With the carton set up the packages 8 are visible through the sight opening 9 as before stated. Additionally, the line of division between the inner ends of the lowermost packages is exposed through the 15 openings 21 and 22 and the merchant may, by inserting a knife blade or the finger nail between the ends of the packages, eject the packages through the opening 34 to dispense the same, it being apparent that when the 20 lowermost package is ejected the next higher package will immediately fall into position to be ejected through the opening 34.

To prevent accidental discharge of the 25 packages through the openings 34, tongues 35 are formed at the lower end of the side walls 27 and 28. These tongues swing outwardly when the packages are ejected but putting such frictional resistance upon the 30 packages as to prevent their accidental dislodgment.

From the foregoing description it will be seen that cartons of this nature may be shipped in large quantities and in the form 35 of blanks and that when they are set up they serve the several functions of displaying the packages, permitting the ready dispensing of the packages and advertising the goods contained within the cartons.

40 It is to be understood that the invention is not limited to the precise construction set forth but that it includes within its purview whatever changes fairly come within either the terms or the spirit of the appended 45 claims.

Having described my invention what I claim is:

1. A shipping and display carton capable 50 of containing a plurality of articles and having an aperture in its front side, a door on each side of said aperture, said doors presenting relatively large surfaces for the display of advertising matter.

2. A shipping and display carton capable 55 of containing a plurality of articles and having an aperture formed in one side, said aperture being of small area relative to said side, and a door on each side of said aperture and integral with said carton.

60 3. A carton adapted to serve as a container for a plurality of articles during transportation and as a sales device, said carton having an aperture in its front wall and doors

integral with said wall and adapted to present a continuous surface for the reception 65 of advertising matter.

4. A carton adapted to serve as a container for a plurality of articles during transportation and as a sales device, said carton having an aperture formed in its front wall, 70 and doors integral with said wall and adapted to present a continuous surface for the reception of advertising matter, said doors being also capable of serving as props to maintain the carton in an upright position. 75

5. A paper carton made from a single blank of paper and comprising a front wall having a sight opening, a rear wall having a central opening through which the packages are accessible for engagement by the 80 fingers and a side wall having a discharge opening formed therein through which the packages may be thrust when engaged through the opening of the rear wall.

6. A carton of the character described 85 formed from a single blank of paper and comprising a front wall having an opening formed therein, wings projecting from the opposite sides of the front wall, end portions at the opposite ends of the front wall, 90 a flap connected to one of said ends, side portions, a rear wall connecting said side portions and one of said end portions, wings carried by the side portions adapted to fold over packages resting against the rear wall, 95 and cutout portions at the lower ends of the side portions, said cutout portions constituting discharge openings for the packages contained in the carton.

7. A structure as recited in claim 6 comprising interengaging elements formed complementally upon the flap and the rear wall 100 for securing these parts together.

8. A structure as recited in claim 6 comprising interengaging elements formed complementally upon the flap and the rear wall 105 for securing these parts together, said flap and wall having alined openings formed therein adjacent the bottom of the carton 110 to permit access to packages contained in the carton for the purpose of ejecting said packages.

9. A structure as recited in claim 6 comprising interengaging elements formed complementally upon the flap and the rear wall 115 for securing these parts together, said flap and wall having alined openings formed therein adjacent the bottom of the carton to permit access to packages contained in the carton for the purpose of ejecting said packages, the opening in the flap being formed 120 by striking an easel wing from said flap.

In testimony whereof I hereunto affix my signature.

ALBERT JAY GANZ.
